(Cl. D48—24)

To all whom it may concern:

Be it known that we, Fay A. Trow and Sophus Rasmussen, both citizens of the United States of America, residing at Albert Lea, county of Freeborn, State of Minnesota, have invented a new, original, and ornamental Design for an Inverted, Down-Burning Gasoline Lantern, of which the following is a specification, reference being made to the accompanying drawing, forming a part hereof, and in which:

Fig. 1 is a perspective view of an inverted, down-burning gasoline lantern, embodying our new design;

Fig. 2 is a side elevational view of the same;
Fig. 3 is a top plan view of the lantern; and
Fig. 4 is a bottom plan view of the same.

We claim:

The ornamental design for an inverted, down-burning gasoline lantern, substantially as shown.
